TORIC LENS TOOL

Henry J. Kratt, Fort Lauderdale, Fla., and Leonard Bronstein, Deerfield, Ill., assignors to The Plastic Contact Lens Company, Chicago, Ill., a corporation of Illinois

Filed Apr. 17, 1961, Ser. No. 103,636
11 Claims. (Cl. 51—217)

Our invention relates to a tool for holding a lens blank in such manner that spherical cutting, grinding and/or polishing of a surface of the blank will result in a final surface which is toric in shape, our tool being particularly adaptable in the manufacture of corneal type, contact lenses.

One object of the invention is to provide a toric lens tool having means to hold a lens blank in such manner that two opposite peripheral portions thereof are held in a different plane than two other opposite peripheral portions thereof at right angles to the two first portions, whereby the lens blank is warped; and thereupon by cutting, grinding and/or polishing a surface of the lens blank to spherical shape, that surface will be toric in shape when the lens blank is released from the tool.

Another object is to provide a lens blank holding tool having means to accurately align a lens blank so that the blank is concentric relative to the tool and a base curve for the lens can be cut or ground in the blank and will be concentric to the blank itself so that subsequent cutting or grinding of a spherical power curve opposite the base curve may be accomplished with assurance that there will be accurate optical alignment of the two curves and at the same time minimizing the time required for completely cutting or grinding the lens.

Still another object is to provide separate means for holding the edge of the lens blank at two pairs of diametrically opposite points, one pair of points being crosswise of the other and the pairs of points being in different planes so as to warp the lens blank before a cutting, grinding and/or finishing operation on one surface thereof whereby when that surface is finished to a spherical shape, it will return to a toric shape when released from our lens holding means.

A further object is to provide means of calibration to indicate the adjustment of the tool for toric surfaces of different dioptric ratio between the major and minor curvatures of the toric lens surface.

Still a further object is to provide a supporting and centering ring for the lens blank which is acted upon by the tool, being warped thereby, and in turn warping the lens blank as the tool is adjusted for the desired degree of such dioptric ratio.

With these and other objects in view, our invention consists in the construction, arrangement and combination of the various parts of our toric lens tool, whereby the objects above contemplated are attained, as hereinafter more fully set forth, pointed out in our claims and illustrated in detail on the accompanying drawings, wherein:

FIG. 1 is an enlarged and exploded perspective view of the parts forming our toric lens tool and a corneal type, contact lens blank suitable for being held by our tool.

FIG. 2 is a front elevation of our toric lens tool and a lens blank held thereby in a collet and spindle of a lathe, the parts being tipped from the FIG. 1 position, top toward the viewer.

FIG. 3 is a vertical sectional view on the line 3—3 of FIG. 2 showing a lathe bit in position for cutting a base curve in the lens, the holder being adjusted so that the lens is not warped.

FIG. 4 is a side elevation, partly in section, of our tool

2

adjusted to receive a lens blank and illustrating the insertion of such blank in the tool.

FIG. 5 is a sectional view similar to FIG. 3 but rotated 90° and shows the cooperation of the lathe spindle and collet with certain portions of the lens holder to axially align them relative to each other and thereby accurately center the lens blank with respect to the axis of rotation of the tool.

FIGS. 6 and 7 are enlarged sectional views similar to FIGS. 3 and 5 respectively showing the tool adjusted for warping the lens blank; and

FIG. 8 is a sectional view similar to FIG. 7 showing the tool and lens blank associated with a polishing tool and pin for polishing the base curve of the lens after it has been cut or ground.

On the accompanying drawings we have used the following reference characters to indicate in general a lens blank and the four parts that form our toric lens tool and reading, in FIG. 1, from top to bottom:

B—Lens blank
R—Warping and supporting ring
W—Warping bar
T—Tool body
S—Adjusting screw

The lens blank B and certain tools for forming a non-toric lens therefrom are shown and claimed in the copending applications of Henry J. Kratt, Serial No. 24,473, filed April 25, 1960, and Serial No. 48,126, filed August 8, 1960.

The present invention has to do with a lens holding tool so designed that the base (or posterior) curve for the lens can be cut, ground and/or polished with cylinder and therefore has a toric shape. The copending application of Kratt, Serial No. 51,167, filed August 22, 1960 shows and claims a somewhat similar tool for forming a toric power (or anterior) curve on a lens. A toric base curve as herein disclosed is accomplished by warping the lens blank.

A tool body T is provided with a pair of diametrically opposite jaws 10 and a bore 12 having a threaded portion 14. The adjusting screw S has a screw portion 16 entering the threads 14 and a knob 18 provided with graduations 20. The graduations may bear suitable indicia (not shown) to be read against a hairline 24 of a transparent pointer 22 extending from the tool body T. A set screw 25 is provided in the body T to bear against a soft metal slug 28 which in turn bears against the threads of the adjusting screw 16 for retaining the adjustment thereof. The body T is further provided with a cross slot 30 adapted to receive the warping bar W. The bar in turn has a central clearance notch 32, at the ends of which supporting shoulders 34 are provided that terminate in circumference engaging shoulders 36 for the warping and supporting ring R.

The ring R preferably has a cone seat 38 to fit a cone surface 40 of the lens blank B, which blank also has a flange 42. In FIGS. 3 and 5 a lathe spindle 44 is shown having a tapered bore to receive a collet 46 of the usual split type (3 splits being illustrated at 48).

The collet of course is adapted to be drawn into the spindle 44 to contract around the lens holding tool shown in FIG. 1 when it is assembled with a lens blank therein as illustrated in these two figures wherein no attempt however has been made to show warpage of the lens blank.

Referring to FIG. 4 the manner of assembly of the tool to hold a blank B is illustrated. The adjusting screw S is in such position as to clear the bottom of the cross slot 30 so that the warping bar W can be slid into position as indicated by the arrow 50. It will be noted that the blank B has been seated in the ring R and the ring in turn positioned for confinement between the shoulders 36

and supported on the shoulders 34. In this position the top of the blank B is lower than the under surface 10^a of the jaws 10 and accordingly the bar W can be slid all the way in as to the position shown in FIG. 5 with the ends of the bar substantially coincident with the circumference of the tool body T. When thus positioned the blank B is located vertically in FIG. 2 by the facing surfaces 13 of the jaws 10, and horizontally by the shoulders 36 of the bar W, whereupon the adjusting screw S may be tightened against the bar W.

The tool and the lens blank are then inserted in the collet 46 while it is loosened, whereupon tightening of the collet by drawing it into the spindle 44 results in final accurate positioning of the bar W with respect to the tool body T as the jaws of the collet are drawn into engagement with the tool. FIGS. 3 and 5 show the screw S tightened only enough to hold the lens whereas actually it will be tightened to the proper degree to form the desired toric base curve as indicated by the graduations 20 and the hairline 24. Upon contact of the threaded portion 16 of the screw S with the lower surface of the bar W in FIGS. 3 and 5 the lens blank will be held between the bar, the jaws 10 and the ring R but not warped. Further tightening will effect warpage as shown in FIGS. 6 and 7 because the jaws 10 in FIG. 6 are holding the flange 42 of the blank B against any further movement whereas the bar W is through its shoulders 34 and the ring R, pressing against the blank intermediate the jaws, thus warping the ring and blank from a non-warped or straight position as in FIG. 3 to the outwardly bowed shape as shown in FIG. 6. Looking at the cross section at right angles as in FIG. 7 the inwardly bowed shape of the lens and ring under the jaws 10 is shown because of the upward movement of the bar W past a non-warped shape as already referred to in FIG. 5. The warped lens blank is now ready for cutting after it is chucked in the lathe collet 46.

FIG. 3 shows the manner of cutting, a lathe bit 52 being shown in a lathe bit holder 54. The lathe bit is adapted to cut a base curve 56 in the lens blank B on a suitable radius indicated r. For this purpose the lathe bit is so mounted as to swing about a vertical axis indicated by a dot 53 and of course may be adjusted for any required length of radius as r.

The lathe bit 52, swinging about the center 53 and through an arc of cut indicated at 60, will cut the surface of the warped lens spherical as it is held by our toric lens tool, and such spherical surfaces are also indicated at 56 in FIGS. 6 and 7. It is now obvious that if the lens blank is released from the position it assumes in FIG. 6 by loosening the adjusting screw S the blank will return to its original shape and the base curve 56 will assume a sharper curvature as indicated by the dot-and-dash line 56^a and will constitute the minor curvature of the toric surface whereas release from the position in FIG. 7 will result in the base curve 56 there shown flattening to the dot-and-dash curvature indicated at 56^b (part of the lens blank being left unsectioned to show 56^b more clearly) which will constitute the major curvature of the toric surface of the lens. Thereafter the opposite or power surface of the blank may be formed as disclosed in the above identified copending patent applications.

Before release of the lens from the tool holder however the base curve 56 (of spherical shape and while the blank remains warped) is polished as illustrated in FIG. 8, our toric lens tool with the lens blank being removed from the collet 46 and associated with a polishing tool 62 having a hemispherical head provided with padding 64 of moleskin, felt, velvet or the like charged with a suitable polishing agent such as stannic oxide and water, and with a polishing pin 66 of a polishing machine, the point of which oscillates on an arc 68 while the tool 62 rotates as indicated by the arrow 70. Thus the surface 56 is polished spherical so that when the lens blank is released from the tool it has a polished toric surface 56^a—56^b, the minor and major curvatures of which are according to the indicated arcs 56^a and 56^b in FIGS. 6 and 7. The screw

S is provided with a seat 67 for the point of the polishing pin, and the tool 62 is rotated by an electric motor or the like (not shown) at a suitable speed for polishing. Accordingly one curvature will be sharper than the other when the blank is released from the tool and thereupon returns to its original shape. Thus a certain dioptric difference to produce a toric base curvature (or cylinder) in the lens has been formed into the posterior surface of the lens.

10 Actually in FIGS. 6 and 7 the degree of warping is somewhat exaggerated, as but a few thousandths of an inch adjusting movement is all that is required. The graduations 20 serve as a micrometer scale which may be calibrated as desired in either thousandths of an inch difference or diopters or difference.

15 From the foregoing specification it will be obvious that we have provided a tool for holding lens blanks in such manner that a surface of the blank can be spherically cut or ground and polished, yet when the blank is released from the tool that surface will be toric in shape. At the same time the dioptric difference between the major and minor curvature of the toric surface may be micrometrically adjusted and conveniently indicated as to such adjustment by cooperation of the graduations 20 and hairline 24 which indicate the degree of warping.

20 Some changes may be made in the construction and arrangement of the parts of our toric lens tool without departing from the real spirit and purpose of our invention, and it is our intention to cover by our claims any modified forms of structure or use of mechanical equivalents which may reasonably be included within their scope.

We claim as our invention:

25 1. In a toric lens tool of the character disclosed, a body having a pair of opposite lens blank edge engaging jaws, said body having crosswise of said jaws a slot, a warping bar slidably received in said slot and having a pair of lens blank edge engaging shoulders, a supporting and warping ring interposed between said shoulders and the blank, and an adjusting screw carried by said body and engageable with said warping bar to move said bar axially of said body and in a direction for warping the lens blank between said jaws and said shoulders.

30 2. In a toric lens tool of the character disclosed, a body having a pair of opposite lens blank edge engaging jaws, said body having crosswise of said jaws a slot, a warping bar slidably received in said slot and having a pair of lens blank edge engaging shoulders, a supporting and warping ring interposed between said shoulders and the blank, an adjusting screw carried by said body and engageable with said warping bar to move said bar axially of said body and in a direction for warping the lens blank between said jaws and said shoulders, and calibration means for said adjusting screw.

35 3. A toric lens tool comprising a body having a pair of opposite lens blank edge engaging jaws, said body having crosswise thereof a slot, a warping bar slidably received in said slot and having a pair of lens blank edge engaging shoulders intermediate said jaws, and an adjusting screw carried by said body and engageable with said warping bar to move the bar axially of the body in a direction for warping the lens blank between said jaws and said shoulders.

40 4. A toric lens tool comprising a body having a pair of opposite lens blank edge engaging jaws, said body having crosswise thereof a slot, a warping bar slidably received in said slot and having a pair of lens blank edge engaging shoulders intermediate said jaws, an adjusting screw carried by said body and engageable with said warping bar to move the bar axially of the body and in a direction for warping the lens blank between said jaws and said shoulders, and calibration means for said adjusting screw.

45 5. In a toric lens tool, a cylindrical body having a pair of opposite lens blank edge engaging jaws for one surface of a lens blank, a warping bar having a pair of lens blank

edge engaging shoulders for the opposite surface of the lens blank, said shoulders being circumferentially intermediate said jaws, a supporting and warping ring interposed between said shoulders and the blank and an adjusting screw carried by said body and engageable with said warping bar to move said bar axially of said body for warping the lens blank between said jaws and said shoulders.

6. In a toric lens tool, a cylindrical body having a pair of opposite lens blank edge engaging jaws for one surface of a lens blank, a warping bar having a pair of lens blank edge engaging shoulders for the opposite surface of the lens blank, said shoulder being circumferentially intermediate said jaws, and an adjusting screw carried by said body and engageable with said warping bar to move said bar axially of said body for warping the lens blank between said jaws and said shoulders.

7. In a toric lens tool, a cylindrical body having a pair of opposite lens blank edge engaging jaws for one surface of a lens blank, a warping bar having a pair of lens blank edge engaging shoulders for the opposite surface of the lens blank, said shoulders being circumferentially intermediate said jaws and the length of said bar being coincident with the diameter of said body, a supporting and warping ring interposed between said shoulders and the blank and an adjusting screw carried by said body and engageable with said warping bar to move said bar axially of said body for warping the lens blank between said jaws and said shoulders.

8. In a toric lens tool, a cylindrical body having a pair of opposite lens blank edge engaging jaws for one surface of a lens blank, a warping bar having a pair of lens blank edge engaging shoulders for the opposite surface of the lens blank, said shoulders being circumferentially intermediate said jaws and the length of said bar being coincident with the diameter of said body, and an adjusting screw carried by said body and engageable with said warping bar to move said bar axially of said body for warping the lens blank between said jaws and said shoulders.

9. A toric lens tool comprising a cylindrical body having a pair of opposite lens blank edge engaging jaws, said body having crosswise thereof a slot, a warping bar of substantially the same length as the diameter of said body, slidably received in said slot and having a pair of

lens blank edge engaging shoulders intermediate said jaws, and an adjusting screw carried by said body and engageable with said warping bar to move the bar axially of the body and in a direction for warping the lens blank between said jaws and said shoulders.

- 5 10. In a toric lens tool, a cylindrical body for reception in a lathe collet, said body having a pair of opposite lens blank edge engaging jaws, said body having crosswise of said jaws a slot, a warping bar slidably received in said slot and having a pair of lens blank edge engaging shoulders, a supporting and warping ring interposed between said shoulders and the blank, means to center said bar and said ring relative to said body, and an adjusting screw carried by said body and engageable with said warping bar to move said bar axially of said body in a direction for warping the lens blank between said jaws and said shoulders.

- 10 15. In a toric lens tool, a cylindrical body having a pair of opposite lens blank edge engaging jaws for one surface of a lens blank, a warping bar having a pair of lens blank edge engaging shoulders for the opposite surface of the lens blank, said shoulder being circumferentially intermediate said jaws, and an adjusting screw carried by said body and engageable with said warping bar to move said bar axially of said body for warping the lens blank between said jaws and said shoulders, said adjusting screw having a polishing pin seat located on the axis of said body and at the end of said tool opposite said jaws and warping bar.

- 20 25. In a toric lens tool, a cylindrical body having a pair of opposite lens blank edge engaging jaws for one surface of a lens blank, a warping bar having a pair of lens blank edge engaging shoulders for the opposite surface of the lens blank, said shoulder being circumferentially intermediate said jaws, and an adjusting screw carried by said body and engageable with said warping bar to move said bar axially of said body for warping the lens blank between said jaws and said shoulders, said adjusting screw having a polishing pin seat located on the axis of said body and at the end of said tool opposite said jaws and warping bar.

- 30 35. In a toric lens tool, a cylindrical body having a pair of opposite lens blank edge engaging jaws for one surface of a lens blank, a warping bar having a pair of lens blank edge engaging shoulders for the opposite surface of the lens blank, said shoulders being circumferentially intermediate said jaws and the length of said bar being coincident with the diameter of said body, and an adjusting screw carried by said body and engageable with said warping bar to move said bar axially of said body for warping the lens blank between said jaws and said shoulders.

- 40 40. In a toric lens tool comprising a cylindrical body having a pair of opposite lens blank edge engaging jaws, said body having crosswise thereof a slot, a warping bar of substantially the same length as the diameter of said body, slidably received in said slot and having a pair of
